(57) **CLAIM**

The ornamental design for a cooking oven with baking stone as shown and described.

DESCRIPTION

The patent or application file contains at least one drawing executed in color. Copies of this patent or patent application publication with color drawing(s) will be provided by the Office upon request and payment of the necessary fee.

1.1: Front perspective shown with baking stone in a configuration of use;

1.2: Front perspective shown with baking stone partially removed;

1.3: Front perspective shown with baking stone removed for clarity of disclosure;

1.4: Rear perspective;

1.5: Top perspective shown with baking stone in a configuration of use;

1.6: Bottom perspective;

1.7: Left side perspective;

1.8: Right side perspective; and

1.9: Bottom front perspective shown with baking stone removed for clarity of disclosure.

In the present application, the parts shown in red are excluded from protection.
